UNITED STATES PATENT OFFICE.

ROBERT SITES, OF HOMER, ILLINOIS.

PNEUMATIC HORSE-BOOT.

SPECIFICATION forming part of Letters Patent No. 581,042, dated April 20, 1897.

Application filed December 13, 1895. Serial No. 572,060. (No model.)

To all whom it may concern:

Be it known that I, ROBERT SITES, a citizen of the United States, residing at Homer, in the county of Champaign and State of Illinois, have invented a new and useful Pneumatic Horse-Boot, of which the following is a specification.

This invention relates to an improvement in strengthening boots or bandages, being especially designed for use upon horses having strained tendons or weak limbs.

The object of the present invention is to provide a simple and efficient boot or bandage which shall comprise a pneumatic or inflatable sack and which when applied to the weakened member, will accommodate itself perfectly to the undulations thereof and thoroughly support and relieve the strained tendons or muscles.

The invention consists in an improved boot or bandage embodying certain novel features and details of construction and arrangement of parts, as hereinafter fully described, illustrated in the drawings, and finally pointed out in the claim.

In the accompanying drawings, Figure 1 is a perspective view of the improved boot or bandage. Fig. 2 is a view in elevation of the same shown opened. Fig. 3 is a horizontal section through the closed boot. Fig. 4 illustrates the application of the improved article and the manner of inflating the same.

Similar numerals of reference designate corresponding parts in the several figures of the drawings.

Much trouble and annoyance have been experienced in the application of boots or bandages of various constructions to the ankles of horses, as by reason of the inability of such article to accommodate itself perfectly to the animal's limb there is a consequent movement or slipping of the boot or bandage which results in drawing upon the weakened tendons and increasing rather than diminishing the trouble. In order to obviate this difficulty, I have devised the following article:

Referring to the accompanying drawings, 1 designates a cylindrical boot, which, it will be understood, may be made of any desired size or material. In the present instance this boot is composed in the main of a section of leather 2 of a length adapting the boot to pass

entirely around and inclose the ankle or limb of the animal, and adjacent to the meeting or lapping edges of such leather are secured a 55 vertical series of straps and buckles 3, with the aid of which the boot or bandage may be tightened. Within the boot is arranged a lining 4, of any soft material, preferably chamois-skin, the same being stitched at its 60 edges to the edges of the leather 2. Between the leather 2 and the lining 4 is inserted an inflatable sack 5, of rubber or other suitable elastic material, which may or may not be confined at its edges adjacent to the edges of 65 the leather and lining. This sack 5 is provided with an outwardly-projecting hollow valve-stem 6, which preferably projects forward through an opening 7 in the leather 2, said valve-stem being provided with a valve 70 of any approved construction, adapting the sack 5 to be inflated or deflated, as required.

Reinforcements 8 and 9, of leather or other suitable material, are stitched upon the inside of the boot at points where the animal 75 interferes, so as to prevent the too rapid wearing out of the boot and increasing the life thereof.

The boots or bandages constructed as above described are made in rights and lefts, so that 80 the securing buckles and straps are on the outside, as shown in Fig. 4, and so that the valve-stems project forwardly in convenient position to admit of the application of an air-pump. Upon inflation the inside lining is 85 pressed firmly against the member to which the device is applied and accommodates itself perfectly to the undulations thereof, so that the boot or bandage exerts an equal pressure at all points and is effectually locked against 90 slipping or any movement whatever upon such member. On account of this absence of movement there can be no chafing nor drawing upon the tendons, and the latter will be thoroughly supported in proper place and 95 the member to which the boot or bandage is applied materially strengthened and braced. The device, with slight modification, may also be adapted for use in connection with sprained wrists or weak ankles and as a bandage in

100 surgical uses, as by inflating the same tightly circulation may be completely arrested in a very short space of time. The inside lining 4 is preferably extended beyond the inside

lapping edge of the boot or bandage, so as to afford a smooth and even inner surface there-to and prevent such edge from chafing the member to which it is applied.

5 Changes in the form, proportion, and minor details of construction may be resorted to without departing from the spirit or sacrificing any of the advantages of this invention.

Having thus described the invention, what is claimed as new is—

10 The herein-described bandage composed of an outer covering of stiff non-stretchable material of oblong rectangular shape, a lining of soft material stitched at or near its edges to said outer covering and having a projecting edge portion to provide an under lap to the edges of the bandage when applied, an inflatable sack interposed between the covering and lining and adapted when inflated to 15 be confined between the cover and lining to cause the latter to conform to and bear with

equal pressure against all parts of the mem-
ber confined within the bandage, a valve-
stem communicating with the inflatable sack
and projecting through the covering, a par-
allel reinforcement secured to the covering,
a series of binding-straps secured to one edge
of the bandage, and buckles attached to short
straps stitched upon the outside of the band-
age some distance inside the opposite outer 25
edge, and a reinforcing-strip 9 attached in
rear of the buckle, said bandage designed for
application to a defective or injured arm or
limb, substantially as described.

In testimony that I claim the foregoing as 30
my own I have hereto affixed my signature in
the presence of two witnesses.

ROBERT SITES.
